UNITED STATES PATENT OFFICE.

PAUL W. FLEISCHER, OF NEW YORK, N. Y., ASSIGNOR TO AMERICAN CAN COMPANY,
A CORPORATION OF NEW JERSEY.

CAN CLOSING AND MARKING MACHINE.

1,200,332.

Specification of Letters Patent.

Patented Oct. 3, 1916.

Application filed December 1, 1915. Serial No. 64,495.

To all whom it may concern:

Be it known that I, PAUL W. FLEISCHER, a citizen of the United States, residing in New York, in the county of New York and State of New York, have invented a new and useful Improvement in Can Closing and Marking Machines, of which the following is a specification.

The invention relates to can closing machines, and particularly to such as employ a marking or stamping means for impressing dates, characters or identifying marks on the cans in connection with the can closing operation, the object being to identify the closed cans with the closing operation in respect of any desired data, such as time, place, agency, nature of the packed product, etc.

The invention consists in the parts and combinations hereinafter set forth and claimed.

In order to make the invention more clearly understood there are shown in the accompanying drawings means for carrying the same into practical effect, without limiting the improvements, in their useful applications, to the particular construction which, for the purpose of example, has been made the subject of illustration.

In said drawings: Figure 1 is a front elevation of a portion of a can closing machine embodying the invention. Fig. 2 is a side view looking toward the right hand end of Fig. 1. Fig. 3 is a perspective view of the marking device separated from the closing machine. Fig. 4 is a longitudinal sectional view of the end of the marker lever.

Referring to the drawings, 1 indicates a substantially horizontal table on which the filled cans are supported and along the surface of which they are successively propelled in spaced arrangement to the seaming head 2, by an intermittently rotating carrier or turret 3. This carrier is mounted on a vertical shaft 4 and formed with can-engaging and propelling recesses 5. The cans to be closed are supplied to this carrier by any suitable automatic means (not shown) or manually. The cans are retained in the recesses 5 until they have been operated on by the seaming head and closed, by an external guide rail 6. The can ends are automatically supplied to the top of each

can before or as it is elevated to the seaming head, by any suitable can end feeding device (not shown). The can is so elevated at the proper instant by a bottom plunger or chuck 7 which, after the closing operation, descends and leaves the can at the level of the top of the table 1. A can so elevated into the seaming head is indicated in dotted lines at a.

The succeeding rotation of the carrier 3, with the aid of a deflecting and outwardly curved switch rail 8, forces the closed cans outward out of engagement with the carrier, and the cans successively and intermittently push one another on to an auxiliary table or support 9 which is attached to and may be considered as a continuation of the table 1. As each can arrives at the position indicated in dotted lines at a' it pauses under the marking device in position to be marked or stamped by the latter.

The fixed framework of the machine carries or has attached thereto the tables 1 and 9 and is provided with suitable bearings for the operative parts. A portion of said frame is indicated in dotted lines at 10. 11 is the vertical rotary spindle which carries the seaming head, a bearing for which spindle is indicated at 12. 13 is the yoke lever which vertically reciprocates the seaming head cams 14, which latter cause the radial movement of the seaming rolls 15 in a known manner. 16 is the vertical cam shaft of the closing machine.

Projecting from the framework of the machine is a horizontal rod 17 having a longitudinal key way 18 therein extending its entire length. This rod has slidably mounted thereon the frame or bracket 19 of the can marking device, which is held against rotation by a key 20 coacting with the keyway in the rod but which can be adjusted along the rod relative to the point at which the closed cans pause in their movement from the seaming head. The said bracket is positively locked in the desired position on the rod by means of a set screw 21.

At the outer extremity of the bracket and integral therewith is a vertical rectangular guide 22. Mounted to reciprocate vertically within this guide is a slide 23 having a pivotal connection 24 at its upper extremity with a link 25, which extends upwardly and

is pivotally connected by a swivel 26 to the outer arm of a lever or rocker arm 27 mounted on the upper part of the framework of the machine. This rocker arm has 5 a roller 28 at its inner end which engages a circular cam 29 fixed at the upper part of the vertical cam shaft 16 of the machine. Attached to a collar 30 on the link is a coiled spring 31 the other end of which is fastened 10 to the bracket at 32. This spring tends to keep the roller 28 on the rocker arm in engagement with the face of the cam 29. The rod is vertically adjustable in the swivel by nuts 33 secured on the rod, to provide 15 for adjustment for marking cans of different heights.

At the lower extremity of the slide is pivoted a type lever holder 34 which is bifurcated to receive the lower end of the 20 slide. The fingers of this bifurcated portion extend at an angle to the line of the type holder arm. The inner finger 35 is slightly longer than the outer finger 36 and engages a roller 37 mounted on a journal 25 38 which latter is adjustably fixed in a vertical slot 39 in a downwardly projecting lug 40 on the bracket. It will be seen that this journal may be adjusted upwardly or downwardly in this slot and locked in its desired 30 position by a nut 41 on the inner end of the journal. When this nut is tightened it will bind the lug between the nut and a collar 42 on the journal.

The pivot pin 43 of the type holder lever 35 extends inwardly and terminates in a head 44. Between this head and the longer finger 35 of the type holder is interposed a coiled spring 45. One end of this spring engages the head mentioned while the other 40 extremity engages the finger 35. This spring acts to normally hold the type holder arm in a vertical marking position over the can, as seen in dotted lines in Fig. 1, the same being prevented from rotating farther than 45 a vertical position by a pin 46 fixed in the shorter finger of the type holder, which pin engages the sides of the slide rod when the action of the spring 45 has caused the type holder to turn to the before mentioned vertical printing position.

The lower part of the type holder is horizontally recessed and adapted to receive a type bar 47 which in turn holds the rubber stamp or type 48. The type holder has a 55 vertical circular aperture in it designed to hold a coiled spring 49 which bears against the type bar. This construction permits enough give to prevent the face of the type from being broken or marred when it comes into engagement with either the can end or the inking roll 50. The inking roll is rotatably mounted on a stud shaft 51 secured at one end to a bracket arm 52.

60 The upper extremity of this bracket arm is slotted at 53 and is adjustably secured by

means of a bolt 54 through this slot to a projecting lug 55 on the main supporting bracket of the printing device.

In operation as the cam on the vertical drive shaft revolves it will actuate the 70 rocker arm 27, which in turn, through the medium of the link or rod 25, will vertically reciprocate the slide 23 of the printing device. It will be understood from the above description that as the slide rod descends 75 the action of the coiled spring 45 will cause the type holder to leave the inking roll and keep the finger 35 against the roller until the type holder assumes a vertical position, further action of the spring to throw the 80 type holder out of this vertical position being arrested by the pin 46 coming into contact with the slide. The slide rod and type holder then both descend in alinement, the longer finger 35 leaving its engagement 85 with the roller, and type 48 perform their printing operation on the closed can end. On the succeeding half revolution of the cam 29 the roller 28 is depressed (Fig. 1), restoring the parts to non-printing position. 90 It is to be observed that the marking impression on the can is performed by a yielding force, that of the spring 31, and not positively by the cam. As the slide 23 travels upward the finger 35 of the type 95 holder engages its roller, thus throwing the type holder around its pivot against the action of the coiled spring 45, until the type again engage the inking roller pad. (Fig. 3.) The adjustment of the marker along 100 the rod 17 will accommodate it to the proper printing points, where the cans pause as they are ejected from the carrier, cans of different diameters being ejected to different stopping points. By the adjustment of the 105 arm 52 or journal 38, or both, the proper inking of the type is insured. The marked cans pass off to a slide or conveyer (not shown) or are removed manually, as is most convenient. The elongated marker-actuating 110 spring 31 has such range of action and capacity for yielding that no adjustment of the marker up or down, for cans of different heights, is necessary in many or most cases.

115 By "seaming head" I include various can end attaching means. Such means may be a clencher which crimps the head loosely on to a can, all around the circumference or in spots. Also, when the seaming head is used, 120 only the first operation or curling roll may be put in operation, the complete hermetic seaming by the second operation being done by any suitable means after processing the filled and partly or loosely closed can; and the words "closing machine" are not limited 125 to a machine which hermetically closes the cans.

What is claimed is:

1. In a can closing and marking machine, 130

in combination: a seaming head having a vertical axis; means for feeding cans to be closed under the said seaming head, and beyond the seaming station after they are closed, to a marking station; a vertically reciprocating marking device at the marking station; a cam shaft having a cam thereon; connections from said cam for moving the marking device in one direction; and a 10 spring for moving the marking device in the other direction.

2. In a can closing machine, in combination: a seaming head; means for feeding intermittently cans to and from the seaming head; a can guide along which the cans push one another successively into marking position; an upwardly and downwardly movable marking device; and means for raising and depressing the marking device to cause 15 the cans to be successively marked as they reach the marking position.

3. In a can closing and marking machine, in combination: a seaming head; means for feeding cans to and from the said seaming head; a guide for directing the closed and intermittently propelled cans to the marking station; a horizontally adjustable marker support; and a vertically reciprocating marking device on said support.

30 4. In a can closing and marking machine, in combination: a seaming head; means for feeding cans to be closed to and from said seaming head to a marking station; a marker arranged at said marking station; 35 mechanism for actuating the marker; and means for adjusting the marker parallel with the path of the cans.

5. In a can closing machine, in combination: a seaming head; means for feeding intermittently cans to and from the seaming head; an upwardly and downwardly movable marking device; power mechanism for raising the marking device; and an actuating spring for depressing the marking device to cause it to make an impression when it is released by the said power mechanism.

40 6. In a can closing machine, in combination: a seaming head; means for feeding intermittently cans to and from the seaming head; a can guiding means; an extended marker support; an upwardly and downwardly movable marking device adjustable along said support; power mechanism for raising the marking device; and a spring 50 for depressing the marking device to cause it to make an impression when it is released by the said power mechanism.

55 7. In a can closing machine, in combination: a seaming head; means for feeding intermittently cans to and from the seaming head; an upwardly and downwardly movable marking device; power mechanism for raising the marking device; and an elongated marker-actuating spring for depressing 60 the marking device to cause it to make

an impression when it is released by the said power mechanism.

8. In a can closing and marking machine, in combination: a seaming head; an intermittently rotary can carrier having means 70 for holding and advancing cans to and from the seaming head; guiding means whereby the closed cans are caused to propel one another out of and beyond the said carrier intermittently to a marking station; a marking device operatively arranged at the said marking station; and means for actuating the marking device, comprising an elongated actuating spring.

9. In a can closing and marking machine, 80 in combination: a seaming head; an intermittently rotary can carrier having means for holding and advancing cans to and from the seaming head; means whereby the closed cans are caused to be propelled out of and 85 beyond the said carrier intermittently to a marking station; a marking device operatively arranged at the said marking station; and means for actuating the marking device, comprising an elongated actuating 90 spring.

10. In a can closing and marking machine, in combination: a seaming head having a vertical axis; means for feeding cans to be closed under the said seaming head, 95 and beyond the seaming station after they are closed, to a marking station; a vertically reciprocating marking device at the marking station; a cam shaft having a cam thereon; connections from said cam for raising the 100 marking device; and a spring for depressing the marking device.

11. In a can closing machine, in combination: a seaming head; means for feeding cans to and from the seaming head, said feeding means giving to the cans an intermittent movement; a vertically reciprocable slide provided at its lower end with marking devices pivotally connected with the slide; an inking pad; means for causing the 110 marking devices to be turned into vertical printing position and into inking position in contact with the said inking pad; power mechanism for raising the slide; and a spring for depressing the slide to cause an 115 impression by the marking devices when the slide is released by the said power mechanism.

12. In a can closing machine, in combination: a seaming head; means for feeding cans 120 to and from said seaming head, said feeding means giving to the same an intermittent movement; a vertically reciprocable slide provided at its lower end with marking devices pivotally connected with the slide; an inking pad; means for causing the marking devices to be turned into vertical printing position and into inking position in contact with the said inking pad; a cam shaft parallel with the axis of the seaming head and a 130

horizontal cam for raising the slide; and a spring for depressing the slide to cause an impression by the marking devices when the slide is released by the said power mechanism.

13. In a can closing machine, in combination: a seaming head; means for feeding cans to and from said seaming head, said feeding means giving to the cans an intermittent movement and causing them to push one another to the marking station; a vertically reciprocable slide provided at its lower end with marking devices pivotally connected with the slide; an inking pad; means for causing the marking devices to be turned into vertical printing position and into inking position in contact with the said inking pad; power mechanism for raising the slide; and a spring for depressing the slide to cause an impression by the marking devices when the slide is released by the said power mechanism.

14. In a can closing machine, in combination: a seaming head; means for feeding cans to and from said seaming head, said feeding means giving to the cans an intermittent movement; a vertically reciprocable slide provided at its lower end with marking devices pivotally connected with the slide; means for adjusting said slide in directions parallel with the path of the cans; an inking pad; means for causing the marking devices to be turned into vertical printing position and into inking position in contact with the said inking pad; power mechanism for raising the slide; and a spring for depressing the slide to cause an impression by the marking devices when the slide is released by the said power mechanism.

15. In a can closing and marking machine, in combination: a seaming head; means for feeding cans to and from the seaming head; a horizontally adjustable marker support; a vertically reciprocating slide operating in the said support; a marking device pivoted to the said slide; an arm fixed on the said marking device; an adjustably fixed roller in the path of the said arm for turning the marking device on its pivot when it is elevated; means for temporarily holding the marking device in printing position when it is depressed; means for turning the marking device on its pivot when it is depressed; and an adjustable inking pad which is engaged by the type of the marking device when the latter is elevated and turned on its pivot.

16. In a can closing and marking machine, in combination: a seaming head; means for feeding cans to and from the said seaming head; a horizontally adjustable

marker support; a vertically reciprocating slide operating in the said support; a marking device pivoted to the said slide; an arm fixed on the said marking device; an adjustably fixed roller in the path of the said arm for turning the marking device on its pivot when it is elevated; a pin on the marking device engageable with the slide to hold the marking device in printing position when it is depressed; means for turning the marking device on its pivot when it is depressed; and an adjustable inking pad which is engaged by the type of the marking device when the latter is elevated and turned on its pivot.

17. In a can closing and marking machine, in combination: a seaming head; means for feeding cans to and from the said seaming head; a guide for directing the closed and intermittently propelled cans to the marking station; a horizontally adjustable marker support; a vertically reciprocating slide operating in the said support; a marking device pivoted to the said slide; an arm fixed on the said marking device; an adjustably fixed roller in the path of the said arm for turning the marking device on its pivot when it is elevated; a pin on the marking device engageable with the slide to hold the marking device in printing position when it is depressed; means for turning the marking device on its pivot when it is depressed; and an adjustable inking pad which is engaged by the type of the marking device when the latter is elevated and turned on its pivot.

18. In a can closing and marking machine, in combination: a seaming head; means for feeding the cans to and from the said seaming head; a guide for directing the closed and intermittently propelled cans to the marking station; a horizontally adjustable marker support; a bracket on which said support is so adjustable; a vertically reciprocating slide operating said support; a marking device pivoted to the said slide; means for turning the marking device on its pivot when it is depressed; an adjustable inking roll adjacent the marking device; means for turning the said marking device on its pivot when it is raised to engage the said inking roll; a rocker arm; a link connecting the rocker arm with the slide and adapted to raise the said slide; a cam for raising the outer end of the rocker arm; and a spring connecting the link with the said marker support.

In testimony whereof I have affixed my signature hereto.

PAUL W. FLEISCHER.
